UNITED STATES PATENT OFFICE.

JAMES J. WOOD, OF BROOKLYN, NEW YORK.

FOCUSING ARC LAMP.

SPECIFICATION forming part of Letters Patent No. 407,915, dated July 30, 1889.

Application filed October 1, 1888. Serial No. 286,920. (No model.)

To all whom it may concern:

Be it known that I, JAMES J. WOOD, of Brooklyn, Kings county, New York, have invented certain new and useful Improvements 5 in Focusing Electric Lamps, of which the following is a specification.

This invention relates to electric-arc lamps wherein both the positive and negative carbons are connected to and moved by the 10 feeding mechanism, the movements imparted to them being so speeded relatively as to maintain the arc in an invariable position during the consumption of the carbons. Lamps of this character are known as "focusing lamps," their principal use being in connection with concave mirrors or convex lenses, or both, by means of which the rays of light from the lamp are concentrated and projected in approximately parallel direction. Lamps of this character are used as 15 head-lights, signal-lights, search-lights, &c.

In focusing electric lamps prior to my present invention, the construction and arrangement of the parts have usually been such 20 that the carbon pencils were located above the mechanism case or "head," the axis of the carbons being usually within the circumference of the case. An example of such a focusing-lamp is found in my patent, No. 279,512, dated June 12, 1883. Such prior focusing-lamps have been found subject to 25 the disadvantage of occupying an inconvenient amount of vertical space from the arc or focus downward to the base of the lamp, so that when applied in a reflector-casing the 30 reflector was necessarily elevated considerably above the bottom of the casing, or the base of the lamp had to project through the bottom of the casing or into a downward 35 extension thereof constructed to receive it. As applied to those projector-casings which are 40 hung in trunnions in order that the beam of light projected may be inclined upwardly or downwardly, such lamps have also been subject to the serious disadvantage of concentrating 45 the weight too greatly beneath the focal axis, (which axis is preferably also the pivotal axis of the trunnions,) thereby necessitating that the upper part of the casing 50 should be heavily counterbalanced in order to approximately counterbalance the cas-

ing and bring its center of gravity into close approximation with its axis of suspension, so that it can be easily turned to any inclination by the operator. Focusing-lamps have 55 also been proposed in which the carbon-supports and mechanism have been arranged to one side of the focal axis of the reflector; but such lamps are subject to other defects quite as serious as those of the more usual lamps 60 already described.

My invention aims, chiefly, to overcome the disadvantages of prior constructions, and provide a focusing-lamp which shall be as compact as possible, the dimensions of which 65 shall be distributed as nearly as possible above and below the focal axis, and the weight of which shall be so distributed that it shall act to counterbalance the weight of the reflector in a pivoted projector-casing 70 and avoid the necessity of idle counterbalancing-weights.

My invention also provides several improvements in the construction and method of operation of focusing-lamps and in the 75 regulator or feeding mechanism thereof.

Figure 1 of the accompanying drawings is a side elevation of my improved lamp inclosed in a pivoted projector-casing, which latter is shown in vertical mid-section. Fig. 2 is a 80 front elevation of my improved lamp removed from the projector-casing and shown on a larger scale, the carbons being omitted. Fig. 3 is a vertical transverse mid-section of the mechanism-case, standard, and base of the 85 lamp, cut in the plane of the line 3 3 in Figs. 1 and 4. Fig. 4 is a plan of the base portion of the lamp in horizontal section on line 4 4 in Fig. 3. Fig. 5 is a horizontal section, on a larger scale, through the mechanism-case in 90 the plane of the line 5 5 in Figs. 1 and 3. Fig. 6 is a detail view of the negative-carbon holder.

Referring first to Fig. 1, let A designate my improved focusing-lamp as a whole, and B 95 the projector-casing inclosing it and having a concave or parabolic mirror B', fixed in it, as usual. The casing B is hung upon trunnions, one of which is shown in dotted lines supported in bearings in the upright frame B'', 100 one arm of which is shown in full and dotted lines. The pivotal axis of the trunnions ex-

tends transversely through the casing and intersects the focus of the reflector and also the electric arc.

For a full illustration and description of the projector here shown in part, reference is made to my application for patent on improvements in electric projectors, executed and filed simultaneously herewith, (application, Serial No. 286,919, filed October 1, 1888.) The portions of the projector and projector-casing shown involve no especial novelty, but are in general of well-known construction, and I do not deem it necessary to further describe them.

15 The electric lamp A is constructed with the usual head or mechanism-case C, and the positive and negative carbon holders D and D', which carry the positive and negative carbons or pencils E and E'. The carbons project through holes a and a' in the reflector B', as usual, and come together in the focus of the reflector.

The peculiar feature which characterizes my improved lamp is the arrangement of the carbons in front of the mechanism-case C, as clearly shown in Fig. 1. This arrangement brings the case C and the standard and base supporting it behind the focus of the reflector, instead of underneath the same or to one side thereof, as heretofore, so that their weight serves to counterbalance the weight of the reflector, since it comes chiefly on the opposite side of the pivotal axis. This arrangement also enables the entire lamp to be brought within the cylindrical walls of the projector-casing, with the exception of the upper part of the positive-carbon holder, which projects, as heretofore, above the upper circumference of the cylindrical portion of the casing 40 and enters the usual hood b, constructed to receive it. With the best prior constructions of focusing lamps it has been necessary to form the casing B with a deep downward extension or pocket to receive the mechanism-case C and its supporting-standard and base, so that the weight of these portions was brought beneath and at a considerable distance from the axis of suspension, and not only failed to counterbalance the weight of the reflector, but 45 also, in order that the projector-casing might be balanced on its trunnion-axis, required itself to be counterbalanced by the fitting of heavy balancing-weights into the upper portion of the casing, thereby making the latter 50 excessively heavy and consequently rendering it difficult to operate the projector and rendering the latter clumsy and unwieldy. My invention not only renders the projector much more compact, but also entirely removes 55 the necessity of the idle weights for counterbalancing the projector-casing.

The mechanism-case C is mounted on a standard F, arranged centrally and vertically beneath it, which standard terminates in a bottom plate F', which rests on a base G. This base is fastened by screws or otherwise to a wooden board G', which is fixed to the bottom

of the projector-casing. Through the medium of the standard and base—the construction of which will be presently explained—the case 70 C may be raised and lowered bodily or moved forward and back or laterally, in order that the arc may be brought by adjustment to the exact focus of the reflector.

The carbon-holders D and D' are of novel 75 construction. Vertical guides or slideways H H are fastened to the mechanism-case C, preferably directly in front thereof, and the carbon-holders D D' consist of bracket-arms d d', provided with any usual clamps c c' for 80 gripping the carbons and terminating in slides J J', which move up and down against the guides H H, being guided and held in proper relative position by the latter. The carbon-holders are provided, respectively, with vertical 85 racks e e', the former being attached at its upper end to the positive holder and the latter at its lower end to a negative holder, and extending past each other at a point between the holders, when they are brought close 90 together, at which point the racks are engaged by the respective pinions f f' on a spindle or shaft K, which passes within the case C and is actuated by the feeding or regulating mechanism, as will presently be described. The 95 pinion f' is of twice the diameter of the pinion f, and is engaged by its rack e on one side of its axis, while the other pinion is engaged by the rack e' on the opposite side of the axis, so that by the rotation of the shaft K 100 the positive-carbon holder has a feeding movement imparted to it at twice the speed of the movement imparted to the negative holder, as usual in focusing lamps, in order to compensate for the greater rate of consumption 105 of the positive carbon.

The particular construction of guides shown, and which is preferred, consists of two vertical parallel rods H H, arranged side by side close in front of the mechanism-case, 110 fastened to the latter by a plate H', which engages them near their middle, and tied together at top and bottom by cross-heads h and h'. The carbon-holder slides J J' consist of tubes fitting freely and sliding on the rods 115 H H, the two tubes on each slide being connected together by an intervening plate or web j, from which the bracket d or d' springs. The racks e e' are guided and kept in engagement with the pinions f f' by means of a 120 frame L, clamped on the rods H H above the plate H', and consisting in the construction shown of two collars or rack-guides fastened by set-screws on the respective rods, and a cross-bar L' screwed to them and extending 125 across from one to the other, and the middle portion of which receives and forms a bearing for the end of the feeding-shaft K. Rollers x x are provided in the rack-guides to take the thrust of the racks. By means of 130 this construction the carbon-holders are provided with a steady and unyielding mounting and their exact parallel movement is assured. The advantage is also gained of avoiding the

passage of the rods through holes in the top and bottom plates or heads of the mechanism case, which holes are liable to admit moisture or dust. With my improved construction the 5 only opening in the mechanism case is the small hole through which the shaft K passes out. This construction of guides also possesses the advantage of greater compactness than could be attained if the carbon-holders were formed 10 with sliding rods as usual.

The upper-carbon holder is provided with a counterpoise-weight w, mounted on arms projecting rearwardly from the slide J, which serves to counterpoise the holder and avoids 15 the tendency to tilt due to the weight of its arm d, clamp c, and the long carbon being entirely to one side of the axis of the guides H. The lower-carbon holder might be similarly counterbalanced; but I do not consider 20 it necessary.

I will now describe the feeding mechanism within the case C, with reference especially to Figs. 3 and 5. In general this mechanism is of the same construction as that disclosed 25 in several prior patents of mine, and is so well known as to require no special description here. The separating and feeding of the carbons are effected by means of a main-circuit magnet or solenoid M and a shunt-magnet N, arranged face to face and acting oppositely upon an H-armature P, the cores of which enter the coils of the magnets M and N. This armature is pivoted to an open 30 armature-lever or tilting frame Q, which is fulcrumed on screws i to the fixed standards 35 of the case, and is retracted by a spring Q'. A train frame or cage R is pivoted to the armature-lever Q at k, and at k' is connected by a parallel-motion link l to the top plate of 40 the mechanism case. The cage R contains the several wheels and spindles of the feeding-train, which train consists, essentially, of a leading pinion m and a detent or scape wheel n, with any desired number of intermediate 45 wheels and spindles in order to multiply the motion to greater or less extent. When the train is elevated by the attraction of the magnet M, which is its normal condition in use, the scape-wheel n is moved by it into engagement 50 with a tooth or stop n', which is mounted on or formed as part of a spring, and the movement of the train is thereby arrested; but when the train is lowered bodily by the tilting of the 55 retracting-spring Q' or the shunt-magnet N, or both, the scape-wheel n is moved down far enough to clear the stop n', whereupon the train is released and the feeding operation takes place until again arrested by the lifting 60 of the train by means of the attraction of the magnet M. This is the usual construction and operation of the feeding mechanism of my lamps.

In all lamps of this description heretofore 65 made the leading or initial pinion m has been made to mesh directly with the rack of the positive-carbon holder, so that the latter is

caused to participate in the bodily up and down movements of the train, by which means the striking of the arc is effected upon the 70 tilting of the armature-lever and lifting of the train by the attraction of the main magnet M. This will be better understood on reference to some of my previous patents—such, for example, as No. 261,289, dated July 18, 75 1882. According to my present construction, however, the leading pinion m meshes with a larger pinion or gear m' on the feeding-shaft K, which shaft is mounted in fixed bearings, 80 its outer end having its bearing in the cross-bar L', as already described, and its inner end having its bearing in a standard l', which descends from the top plate or head of the case C. The operation may be best understood by a comparison of Figs. 2 and 3, which 85 are both views looking from the front. It will be seen that the pinion m engages the gear m' on the same side of the axis of the feeding-shaft K that the positive-holder rack e engages the pinion f. Hence, when the 90 magnet M acts to tilt the lever Q and bodily lift the train, the pinion m, which is held from rotating by the detent of the train, moves upward tangentially to the gear m', and acts on the latter as though it were a rack, thus partly 95 rotating the gear m' and shaft K, and consequently partly rotating the pinion f in the same direction and thereby propelling the rack e upward and lifting the positive-carbon holder and carbon. At the same time 100 the smaller pinion f', having the same degreee of rotating movement imparted by the shaft K, propels its rack e' downward, and thereby lowers the negative-carbon holder and carbon 105 a distance equal to half the lift of the positive holder. Thus the carbons are separated and the arc is formed.

The feeding is effected by the preponderance of weight and mechanical advantage of the positive holder and carbon over the negative holder and carbon, the weight of the former being transmitted through the rack e to the pinion f, at twice the distance from the center of the shaft K that the weight of the negative holder is transmitted through the 110 rack e' to the pinion f', so that by this preponderance of weight and leverage of the positive holder the shaft K has imparted to it a tendency to rotate in the direction which 115 will feed the carbons together. This tendency is normally resisted by the train so long as the attraction of the magnet M keeps the train lifted with its wheel n in engagement with the stop n'; but when, by the increase of the attraction of the shunt-magnet N, due 120 to the lengthening of the arc, the armature is lifted and the train correspondingly lowered, the shaft K is revolved in the feeding direction, first by the bodily downward movement of the pinion m, in which, being non-rotative, 125 it acts like a rack upon the gear m', and subsequently, after the train is released by the freeing of the detent-wheel n, the shaft K is permitted further to rotate in the same direc- 130

tion and to rotate the train with it, until the proper feeding has been effected, whereupon the feed is arrested by the lifting of the train, through the preponderating attraction of the magnet M, until the detent-wheel is again caught by the stop n' .

In my said patent, No. 279,512, there is the same construction of tilting armature-lever and feeding-train having a bodily upward and downward movement; but the train has two leading pinions, one of which engages directly with the rack of the positive-carbon holder and the other of which, on the same spindle of the train, engages with a gear on a shaft mounted in stationary bearings, (and answering to the gear m' and shaft K of my present construction,) which shaft gears with the rack of the negative-carbon holder by means of a pinion, (answering to the pinion f' of my present lamp.) My former construction necessitated, practically, that the rack of the positive carbon should pass through the mechanism-case, and necessitated also the interposition of an insulating-coupling in the negative-feeding shaft. By utilizing the same shaft and stationary bearings as the feeding-shaft for both carbon-holders I effect some simplification of the mechanism and enable the racks of the carbon-holders to be arranged exterior to the mechanism-case, which is practically of great advantage.

I will not herein describe the construction of automatic relighting cut-out which is shown, or the resistance-coil, or the manual switch for short-circuiting the lamp, since these features are fully illustrated and described in my application, Serial No. 246,559, filed August 10, 1887.

I will now describe the circuit-connections. The current enters by the positive binding-post p and passes thence into the metallic frame of the lamp, flowing through the plate H' into the rods H H , and thence through the positive holder D and positive carbon E to the negative carbon E' , and through the clamp c' thereof, the shank of which passes through the larger end of the bracket d , and is insulated therefrom, as shown in section in Fig. 6, and thence by the two flexible insulated wires q q to a boss q' , which is insulated from and passes through the bottom plate of the mechanism-case, and which within the case terminates in a binding-post, to which is connected one terminal r of the coils of the main-circuit magnet M, through which the current flows, and passes out by the other terminal r' thereof, which leads to the negative binding-post p' , by which the current passes off to the line. The connections of the shunt-magnet coils and the resistance-coil for the relighting cut-out are well understood and require no description. It will be observed that the main-circuit connections in my present lamp differ from those common in focusing-lamps, in that the clamp c' of the negative-carbon holder is insulated from the bracket of the holder by a sheath

of heat-resisting insulation—such as mica—and is connected with the circuit in the mechanism-case through the medium of the flexible wires q q , of which I use two, by preference and as a protection against the accidental rupture of one of them, although one wire alone might be employed.

I have said that the standard F, which supports the lamp, is mounted adjustably on the base-plate G, so that the lamp may be moved to different positions in a horizontal plane in order to adjust the position of the axis of the carbons relatively to the reflector. This result is accomplished by the construction best shown in Figs. 3 and 4. The standard F terminates at its bottom in a plate or disk F' , to which the upper and tubular portion of the stem is connected through the medium of an arched frame F'' . The top of the base-plate G and the bottom of the plate F' are made flat, so that the latter can rest upon the former and may be moved thereon to different positions. The plate F' has a slot s formed through it and extending in fore-and-aft direction or in a direction toward and from the axis of the carbons, as shown in Fig. 4, where the position of the carbons is indicated at E. A set-screw S passes through the slot s and screws into the center of the base-plate G, a washer being preferably interposed between the head of the screw and the top of the plate F' , as shown. By loosening the screw S the plate F' is freed, and may be oscillated on the base-plate or moved fore and aft in order to bring the carbons to the proper position in the reflector, after which, by screwing down the screw S, the plate F' will be clamped firmly in place.

I provide for the adjustment of the carbons in vertical direction, in order to adjust the carbons up or down and thereby bring it into the focus of the reflector by raising and lowering the case C bodily by means of a telescopic construction of the standard F, as has been done heretofore. The case C is mounted on a tube t , the lower portion of which is screw-threaded and slides telescopically into a tube t' , which is fixed to the arched frame F'' . A nut u turns freely on the upper end of the tube t' , and engages the screw-thread of the tube t , so that as the nut is turned the tube t is propelled up or down. Heretofore, in extensible standards of this character, the inner tube has been prevented from turning by means of a pin-and-slot connection with some stationary part, such as a pin projecting inwardly from the tube t' and entering a vertical slot in the tube t . Such construction has been found objectionable because when the pin and slot become worn, as they soon do by use, a looseness or lost motion is developed in lateral direction, which becomes greater the greater the distance from the axial center, so that at the carbons it amounts to a sufficient play to materially disturb the focal position of the carbons relatively to the reflector. In my improved lamp this defect is entirely over-

come by a different construction of vertical guide. In the bottom plate of the standard F, and as far from the center of the screw *t* as can be, is fixed a vertical pin or other 5 equivalent guide *y*, the axis of which is parallel with that of the telescopic screw of the standard. The lower cross-head *h'* of the guide-rods H H has a backward extension which terminates in a forked guide *v*, embracing 10 the pin *y*, as best shown in Fig. 4. As the mechanism-case C is raised or lowered by the turning of the nut *u*, the guide *v* travels up or down against the pin *y*, and thereby serves to prevent the rotation of the mechanism-case around the screw-axis *t'*. As the axis 15 of the pin *y* is considerably removed from that of the screw *t*, a given degree of lost motion would produce much less play at the carbons than with the pin-and-slot device here- 20 tofore used. The construction is such, furthermore, that wear is much less likely to occur than with a pin-and-slot guide, and the parts can be much more accurately constructed in the first instance. The head of the pin 25 *y* serves as a stop to prevent screwing up the mechanism-case too high, and the lug into which the pin *y* is fastened serves as a downward stop to limit the descent of the mechanism-case. The pin *y* and guide *v* also serve 30 to some extent to steady the guide-rods H H and prevent any spring of the latter. The precise construction of the guides *y v* is not essential, as the pin and fork or notch might be reversed, or any other equivalent guiding 35 construction located at the same point, or in substantially equivalent position, might be substituted.

Heretofore telescopically screw-extensible standards have been operated to raise or 40 lower the mechanism-case and carbons by turning the nut *u* by the hand, it being peripherally milled for this purpose. I now make the nut *u* with bevel gear-teeth and arrange a bevel-pinion *u'* to mesh with it, 45 this pinion being fixed on a short shaft T, on which shaft is a wheel or knob O, by turning which the nut *u* is rotated and the mechanism-case and carbons are propelled up or down. The shaft T is borne by a bracket- 50 arm U, which extends upward from a split sleeve U', which embraces the tube *t'* and can be turned around the latter to cause the shaft T to radiate from the center in any direction desired, whereupon the sleeve is fastened 55 by tightening its clamping-screw. The carbons may be adjusted vertically by reaching the hand inside the projector-easing and turning the wheel O; but when the lamp is inclosed within a casing it is preferable to 60 employ the construction shown in Figs. 1 and 2, where a supplemental shaft T' is coupled to the shaft T by means of a universal joint *w'* and extends out through the projector-easing and has a hand-wheel o' on its outer 65 end. The universal joint enables the position of the lamp to be freely adjusted in horizontal direction by means of the set-screw S

and plates F' and G without interfering with the action of the mechanism for adjusting the carbons vertically. The supplemental shaft 70 T' and universal joint are also desirable in the case of a locomotive head-light, so that the wheel O may be carried back into the cab, the shaft T' being in one or more sections coupled together by universal joints and 75 mounted in any suitable guides or bearings, whereby obstructions on the locomotive may be avoided. It is important that the vertical adjustment of the carbons shall be within immediate control of the engineer, since the 80 position of the arc may be accidentally changed at any instant by the breaking off of one or other of the carbons, which necessitates an adjustment of the carbon-holders up or down in order to restore the arc to co- 85 incidence with the focus of the reflector.

In the front of the case C is set a pointed pin z, (shown in Figs. 1 and 2,) which serves as a gage for indicating the proper position of the focus or arc, and aids in the setting of 90 the lamp and the adjustment of the carbons.

It will be understood that my invention in its broader features is not limited to the construction of the carbon-holders to slide upon fixed vertical guides or guide-rods, or 95 upon the particular construction or arrangement of these guides.

Although I have referred to the arc as being located in front of and on a level with the mechanism-case, it will be understood 100 that it may be somewhat above or below the level of the case, and that the axis of the carbons instead of being in front may be arranged on any side of the case, it being only essential that it be exterior thereto and that 105 the carbons be held from above and below the case, or, in other words, that when the carbon-holders are spread apart to the utmost extent, the one shall be above the case and the other shall be below it. 110

It is also to be understood that the feeding mechanism may be operated by electro-magnets or solenoids and by one or more magnets or solenoids, according to any arrangement that is known in the art as being a substantial equivalent of that shown. 115

I claim as my invention the following defined novel features and combinations, substantially as hereinbefore specified, viz:

1. In a focusing electric lamp, the combination of a mechanism-case, regulating mechanism inclosed therein, vertical guides borne by the case fastened to the exterior thereof and extending above and below the case, the positive and negative carbon holders constructed 120 to slide on said guides, racks exterior to the case attached to the respective carbon-holders and extending vertically past each other, pinions engaging said racks, and a feeding-shaft on which said pinions are fixed, extending 125 into the case and forming part of the regulating mechanism.

2. In a focusing electric lamp, the combination of a mechanism-case, regulating mech-

anism inclosed therein, vertical guides borne by the case fastened to the exterior thereof and extending continuously from top to bottom above and below the case, positive and negative carbon holders constructed with slides engaging and sliding on said guides, the one engaging the upper part of the guides and the other the lower part of the same guides, and each slide movable from its end portion of the guides toward the other slide and to the middle portion of the guides, racks exterior to the case attached to the respective carbon holders and extending vertically past each other, pinions engaging said racks, and a feeding-shaft on which said pinions are fixed, extending into the case and forming part of the regulating mechanism.

3. The combination, with the mechanism-case, fixed vertical guides, and carbon-holders constructed to slide on said guides and having brackets projecting outwardly and carrying the carbon-clamps, of a counter-weight for the carbon-holder mounted on an arm on the side of the slide opposite to the bracket and clamp.

4. The combination, with the mechanism-case C, of exterior vertical guides consisting of rods II II, fastened at their middle portion to the case, and fastened together by cross-heads at their top and bottom ends, and the positive and negative carbon holders D and D', formed with slides J and J', respectively, each of said slides engaging both rods II II, the slide J, movable over the portion of the rods above the fastening to the case, and the slide J', movable over the portion of the rods below such fastening, racks e e', fastened at their ends to the respective holders and extending vertically past each other parallel with the guide-rods, and a feeding-shaft K, near the middle fastening of the guide-rods, having pinions f f' meshing with said racks.

5. In a focusing electric lamp, the combination, with the mechanism-case, and the positive and negative carbon holders and their racks arranged exterior to said case, of exterior pins engaging said racks, a feeding-shaft on which said pinions are fixed, which extends thence within the case and which is mounted in stationary bearings, a feeding-train having a terminal detent-wheel and arranged with its leading pinion meshing with a gear on said shaft and movable bodily up and down, and an electro-magnet having its movable member connected to said train and adapted to impart up or down movement thereto, whereby during said up or down movement the leading pinion of the train meshes tangentially with said gear-wheel and turns the latter after the manner of a rack.

6. The combination, with the mechanism-case and carbon-holders in an axis outside thereof, of a supporting - standard beneath said case terminating in a bottom plate, and a stationary base-plate beneath said bottom plate, with a concentric swiveled connection between said standard and base-plate, where-

by the mechanism-case can be partially rotated axially to move the carbons laterally, in order to readjust their focal position, and a clamping-screw for tightening said standard after adjustment.

7. The combination, with a focusing electric lamp having the axis of its carbon-holders outside of the mechanism-case, of a vertical standard on which its mechanism-case is mounted, said standard terminating in a bottom plate, a stationary base-plate on which said bottom plate rests, and a combined swiveled and sliding connection between the standard and base-plate, consisting of a slot through the bottom plate extending in a direction toward and from the axis of the carbon-holders, and a clamping - screw passing through said slot and engaging the base-plate, whereby the standard may be slid bodily to move the carbons forward or back, or oscillated to displace them laterally, the focal adjustment of the axis of the carbons being thus adjustable by the manipulation of a single screw.

8. The combination, with a focusing electric lamp and its base-plate, of a horizontally-adjustable connection between them, whereby the axis of the carbons may be shifted, a vertical adjustment for the lamp, whereby the are may be raised or lowered, a laterally-projecting shaft geared to the vertical adjusting devices for imparting motion thereto, and a supplemental shaft connected to said shaft through the medium of a universal joint, whereby the mechanism for effecting the vertical adjustment is not influenced by the horizontal adjustment of the lamp.

9. The combination, with a focusing electric lamp, of a telescopically-extensible vertical standard on which it is mounted, a nut turning on one section of said standard and engaging a screw-thread on the other for extending the standard and formed with bevel gear-teeth, and a laterally-projecting shaft having a bevel-pinion engaging the teeth on said nut for communicating rotary movement thereto, with a bearing-arm for supporting said shaft, and a clamping-sleeve embracing the fixed member of the telescopic standard, and adjustable around the latter in order to bring the laterally-projecting shaft to any position around the vertical axis.

10. In a focusing electric lamp, the combination, with the mechanism-case, of a telescopically - extensible vertical standard on which it is mounted, constructed with a stationary section, a vertically-movable section fixed to the mechanism-case, and a nut turning on one of said sections and engaging a screw-thread on the other, exterior guides for preventing the turning of the mechanism-case, constructed with one member fixed to the stationary section of the standard and the other member connected to the mechanism-case, and with stops in connection with said exterior guides for limiting the vertical adjustment of the mechanism-case.

11. In a focusing electric lamp, the combination, with the mechanism-case, the carbon-holders, and vertical guides therefor arranged exterior to the case and fastened thereto, of a telescopically-extensible standard on which the case is mounted, and guides for preventing the turning of the mechanism-case, constructed with one member fixed to the stationary section of the standard and the other member fixed to the lower portion of the carbon-holder guides.
12. In a focusing electric lamp, the combination, with the mechanism-case C, the carbon-holders, and vertical guides H H therefor fixed to the exterior of the case, of the telescopically-extensible standard F, on which the case is mounted, consisting of a movable upper member fixed to the case and a stationary lower member mounted on the bottom plate F', and guides for preventing the turning of the case, consisting of a pin y, fixed to said bottom plate, and a socket-piece v, fixed to the lower portion of the guides H H.
